UNITED STATES PATENT OFFICE

2,467,096

ILLUMINATING DEVICE

Paul M. Ressinger, Chicago, Ill.

Application February 9, 1945, Serial No. 576,914

3 Claims. (Cl. 240—108)

1

My invention relates to an improvement in lighting equipment. One purpose is to provide an ornamental lighting member.

Another purpose is to provide a lighting member which inherently throws a light from an interior light source in a predetermined direction.

Another purpose is to provide a tubular light element which throws light downwardly toward and about the base of a tube or toward a predetermined area to be illuminated.

Another purpose is to provide a light which may advantageously be used in display devices, showcases and the like and which is ornamental and also constitutes an efficient lighting medium.

Another purpose is to provide a lighting element which includes means for preventing direct impingement of light rays upon the eyes of the observer.

Another purpose is to provide a lighting feature which may function as a structural member or support.

Other objects will appear from time to time throughout the specification and claims.

I illustrate my invention more or less diagrammatically in the accompanying drawings, wherein:

Figure 1 is a side elevation with parts broken away and parts in section;

Figure 2 is an axial section on an enlarged scale; and

Figure 3 is a section along the line 3—3 of Figure 2.

Like parts are indicated by like characters throughout the specification and drawings.

Referring to the drawings, 1 indicates a tubular light which may be of any suitable type and preferably has a fitting 2 at each end with any suitable electric contact or contacts 3. The lighting tube or bulb itself does not form part of my invention. Surrounding it, I illustrate a tubular member generally indicated as 4 which may be open at each end as at 5 and which may be formed of any suitable transparent or translucent material 6.

Arranged along the tube are a plurality of generally conic members 7 which may be opaque or less translucent than the intervening portions 6 or may be differentiated in color from the members 6. They may, for example, be of opaque material with a reflective lower face. 10 is any suitable bracket for the bottom of the tube 1. It may be provided with electric contacts not herein shown, to receive the projecting contact or contacts 3 from the base of the tube. The

2

member 10 may be supported as by the flange 11 on any suitable base support floor or wall 12.

13 indicates any suitable securing member such as a bolt or screw. The upper end of the tube 1 extends beneath an upper bracket element 15 shown as mounted by a flange 16 upon any suitable wall or support 17 to which it may be secured by a securing member 18. The member 15 will also be understood to have any suitable receiving contact or socket for the projecting contact or contacts 3 of the upper end of the tube 1.

With the parts in the position of Figures 1 or 2, an interior source of light is surrounded by the outer tube. The members 7 are so spaced and proportioned that no light directly escapes laterally toward the observer, if the members 7 are of opaque material. However, light can freely shine downwardly and outwardly through the intervening transparent or translucent portions 6 and will be effective to illuminate articles positioned about the exterior of the tube 4 or located within the cone of illumination provided by the tube 4.

25 I may form the tube 4 of sufficient strength to serve as a structural member. For example, taking Figure 1 as diagrammatic, the member 10 may receive a base on which the lower end of the tube 4 rests. The member 15 may then rest on the upper end of the tube 4 and the tube 4 may be employed to support any suitable upward structure diagrammatically represented by 15, 16 and 17. For example, in a display structure which might be mounted on the top of a counter or on a floor or suitable support, one or more of the tubes 4 may be used as supports for an upper element.

40 One advantageous use of my invention is in connection with tubes in which the parts 6 are transparent and the parts 7 are opaque. They therefore constitute fixed shutters for preventing the lateral radiation of light from the enclosed light source 1. It may be advantageous to render the lower faces of the members 7 reflective.

45 Another application of my invention is to employ contrasting colors. For example, if the member 6 is transparent, the members 7 may be transparent or translucent or opaque, with the members 6 and 7 of different coloring.

50 My invention can be employed with a variety of materials but I find it preferable to use plastics.

It will be realized that whereas I have shown and described an operative device, still many changes might be made in size, shape, number and disposition of parts without departing materially

from the spirit of my invention. I wish, therefore, that my showing be taken as in a large sense diagrammatic or illustrative, rather than limiting me to my precise showing.

I claim:

1. For use with a tubular light source, a unitary tubular shade of transparent material, said shade having embedded therein a plurality of conic opaque louvre members, the larger ends of said conic members being located adjacent to the outer surface of said tubular member, said conic members extending upwardly and inwardly to terminate adjacent the inner face of said tubular member. 10

2. For use with a tubular light source, a unitary tubular shade of transparent material, said shade having embedded therein a plurality of conic opaque louvre members, the larger ends of said conic members being located adjacent to the outer surface of said tubular member, said conic members extending upwardly and inwardly to terminate adjacent the inner face of said tubular member, said shade being open at each end, and of substantially uniform diameter from end to end. 20

3. An elongated, hollow, cylindrical housing adapted to receive and completely mask a tu- 25

bular light source, said housing comprising alternate conical bands of translucent and opaque material, both types of bands extending from the inside to the outside of the housing, said bands increasing in diameter downwardly, the upper boundary of each opaque band lying in the plane of the lower boundary of the opaque band immediately above it, the inner and outer peripheries of the housing being cylindrical and smooth.

PAUL M. RESSINGER.
